UNITED STATES PATENT OFFICE.

FRANK V. BURTON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

CURRENT-TAP

1,281,907.

Specification of Letters Patent. Patented Oct. 15, 1918.

Application filed November 27, 1915. Serial No. 63,797.

To all whom it may concern:

Be it known that I, FRANK V. BURTON, a citizen of the United States of America, and residing at Bridgeport, in the county 5 of Fairfield and State of Connecticut, have invented a certain new and Improved Current-Tap, of which the following is a specification.

My invention relates to current taps and 10 the object of my invention is to provide a simple and efficient current tap device which may be readily applied to various fittings of standard type to afford a detachable connection for a branch circuit.

15 In the accompanying drawings I have shown my invention applied to a standard electric lamp socket.

Figure 1 is a side elevation of a standard pull socket to which my tap device has been 20 applied;

Fig. 2 is a vertical section therethrough drawn to a larger scale;

Fig. 3 is a detached vertical elevation of the same, partly in section, showing the manner in which the device is installed;

Fig. 4 is a perspective of the tap casing;

Fig. 5 is a side elevation of the tap device alone; and

Fig. 6 is a section on the line 4—4, Fig. 1. 30 In the form here shown my invention is illustrated in conjunction with a pull socket of standard type comprising a cap 10 and shell 11 adapted to be sleeved together and provided within the sleeving area with latching elements of the type shown in the Goodridge Patent No. 958,626. In the normal installation of this socket the shell 11 and cap 10 are latched together and the bushing 12, carried by the cap, is screwed onto a fixture 40 pipe 13. Through the latter the leading-in wires 14 and 15 are introduced to the interior of the socket and are connected to the wire terminals 16 and 17 on the insulating body 18 of the socket. The circuit is completed through the socket lamp terminals 19 and 20 by means of a switch mechanism of any suitable type operated by the pull chain 21. It frequently occurs that a drop light or other supplemental fitting is desired in 50 addition to the lamp carried by the socket.

To afford convenient means from which current may be taken to said supplemental fitting, I provide the present independent tapping appliance for the socket.

55 This tapping appliance comprises a casing

22 of the same general character as that of the socket and provided at one end with latching elements 23 adapted to enter the cap and coöperate with the latching elements thereon, while at its other end it is provided 60 with latching elements 24 adapted to coöperate with the latching elements on the sleeve 11. In other words, the tap casing 22 has at one end latching elements 24 corresponding 65 to those on the cap 10, while at the other end its latching elements 23 correspond to those carried by the shell so that the tap casing telescopically engages and latches with the cap and shell in precisely the same manner as the cap and shell normally latch 70 into engagement with each other. Within the tap casing 22 is an insulating block 25 having secured thereto, on opposite sides of a barrier web 26, a pair of terminal plates 27 and 28, each carrying two binding screws 75 29 and 30. This tap block 25 is provided with a boss 31 adapted to project through an aperture 32 in the casing and pierced by two openings 33 and 34 in which lie terminals 35 and 36, respectively connected to the 80 plates 27 and 28 and adapted to receive the jacks of an attachment plug. The barrier 26 is beveled at 37 opposite the boss 31 to facilitate the adjustment of the tap block in its casing 22 (see Fig. 3).

85 The manner in which the present device is assembled and used is readily understood. When it is desired to insert the appliance in a socket of the type described, the shell 11 is detached from the cap 10 and the wires 90 14 and 15 are freed from the socket wire terminals 16 and 17. The wires are then drawn down far enough to permit them to be attached to the respective wire terminals 29 on the tap block 26 which has previously 95 been removed from its casing 22. Short connecting wires 38 and 39 are then secured to the respective binding screws 30 on the tap block, leaving their other ends free. The tap casing 22 is then adjusted over the 100 tap block by a tilting movement, illustrated in Fig. 3, and pushed up into latching engagement with the cap 10. In this position the tap block is housed by its casing 22, but the ends of wires 38 and 39 project beyond 105 the lower edge thereof a sufficient distance to permit them to be secured to the socket wire terminals 16 and 17, respectively. In order to make this connection the socket body 18 is lifted sufficiently out of the shell 110

11 to expose the wire terminals 16 and 17. After the connection of the free ends of wires 38 and 39 to the socket wire terminals 16 and 17 has been established the shell 11 5 is pushed up into latching engagement with the tap casing 22 and the fitting is now complete and ready for use.

It is obvious that the current is led without interruption to the socket wire terminals 10 16 and 17 as before, while at the same time the tapping terminals 35 and 36 are brought into circuit and afford convenient means for tapping off a branch circuit by means of an attachment plug. The terminals 35 and 36 15 are preferably of such construction and arrangement that they will receive the jacks of standard attachment plugs.

It is obvious that the present tap device 20 may be employed with any fitting having a sleeved casing between the parts of which the tap sleeve 22 may be inserted. Thus it could be used with a pendent switch or a

wall socket, or any other suitable appliance, and I do not limit my invention to the precise structure shown. Moreover, the details 25 of the tap sleeve and block may be variously modified as will readily occur to those skilled in the art without departing from what I claim as my invention.

I claim as my invention:

30 A tap-appliance of the character described, having a sleeve-like tap casing apertured on one side, a tap block of insulating material having a boss adapted to project through said aperture, the side of the block opposite the boss being beveled to facilitate the assembly of the block in its casing.

35 In testimony whereof I have signed my name to this specification, in the presence of two subscribing witnesses.

FRANK V. BURTON.
